GASEOUS ELECTRIC DISCHARGE DEVICE

Robert Rompe, Berlin, and Wolfgang Theuret,
Berlin-Wilmersdorf, Germany, assignors to
General Electric Company, a corporation of
New York

Application September 13, 1937, Serial No. 163,700
In Germany September 15, 1936

1 Claim. (CL 176—122)

The present invention relates to gaseous electric discharge devices generally and more particularly the invention relates to such devices of the type comprising a spherical vessel of vitreous material containing thermionic electrodes spaced apart a distance less than the diameter of said container, a starting gas and a quantity of vaporizable metal the vapor pressure of which is 20 atmospheres or higher during the operation of the device.

The object of the invention is to provide a gaseous electric discharge lamp device of the above type which is useful in optical apparatus and has a long, useful operating life. Another object of the invention is to provide a lamp device of the above type in which the formation of light absorbing deposits of sputtered electrode material on the light transmitting walls of the container is avoided in a positive manner. Still further objects and advantages attaching to the device and to its use and operation will be apparent to those skilled in the art from the following particular description.

In accordance with these objects a gaseous electric discharge lamp device embodying the invention comprises a vitreous container having a spherical part and a cylindrical neck part. The longitudinal axis of the neck part of the container, when prolonged, passes through the center of the spherical part thereof. A pair of thermionic electrodes are mounted in the spherical part of the container and are separated a distance substantially less than the diameter of said spherical container part. The electrodes are supported by current leads passing through the wall of the container and mounted in the same straight line; one of said electrode leads being in the longitudinal axis of the neck part of said container. A bell shaped, open-ended baffle is mounted in the neck part of the container and above the discharge path between said electrodes. The axis of said baffle is coincident with the axis of the neck part of the container.

The lamp device is mounted with the electrodes in a vertical position and with the neck part of the container above the spherical part thereof. In this position the discharge between the electrodes does not deviate from the straight path between the electrodes and the sputtered particles of electrode material are carried upward into the bell-shaped baffle whereby they are deposited. Blackening of the light transmitting walls of the spherical part of the container by the sputtered electrode particles is thus effec-

tively avoided and the lamp has a long useful operating life.

In the drawing accompanying and forming part of this specification an embodiment of the invention is shown in a front elevational, partly 5 sectional view.

Referring to the drawing the gaseous electric discharge lamp device comprises a vitreous container 1, such as a quartz container, having a spherical part and a cylindrical neck part. Two 10 thermionic electrodes 2 and 3 are centrally mounted in the container 1 and are separated a few millimeters from each other in a vertical position. Said electrodes 2 and 3 consist of a material having high electron emission characteristics, such as alkali earth metal oxides contained in a hollow, perforated metal body, such as a perforated tungsten shell. Said container 1 has a starting gas therein, such as neon, at a pressure of about 5 mm. and a quantity of vaporizable metal, such as mercury, in such amount that it is completely vaporized during the operation of the device. Current leads 5 and 6 consisting of tungsten or molybdenum are fused into hard glass or quartz tubes 7 and 8, respectively, 25 which in turn are fused to the container 1 in opposing positions so that the current leads 5 and 6 are in the same straight line. A bell shaped baffle 9 consisting of quartz or hard glass is centrally mounted with respect to the current lead 5 in the upper neck part of the container 1. Said baffle 9 is supported in said container 1 by the quartz or hard glass rods 10 fused thereto and to the neck part of the container 1. The outer surface of the neck part of 30 the container 1 has a metal coating 11 thereon which reflects the heat rays back into said container 1 to maintain this part of the container at as high a temperature as the other parts of said container 1 during the operation of the 35 device.

The device described above is capable of operation at mercury vapor pressures of 20 atmospheres and higher and the sputtered particles of electrode material are swept upward from the 45 electrodes 2 and 3 into the bell shaped baffle or chimney 9 where they are deposited. The inner surface of the spherical part of the container 1 is thus free from light absorbing deposits of sputtered electrode material and the lamp has a 50 long useful operating life.

While we have shown and described and have pointed out in the annexed claim certain novel features of the invention, it will be understood that various omissions, substitutions and changes 55

in the forms and details of the device illustrated and in its use and operation may be made by those skilled in the art without departing from the broad spirit and scope of the invention, for example, the screen 9 is supported in said container 1 by means of metal springs, when desired and other types of thermionic electrodes are used, when desired.

What we claim as new and desire to secure by Letters Patent of the United States, is:—

A gaseous electric discharge lamp device of the high vapor pressure type consisting of a vitreous container, thermionic, activated electrodes and electrode leads sealed therein, a starting gas and a quantity of mercury therein the vapor of which is luminosity producing during the operation of said device, said container consisting of a tubular neck part and a spherical part, the longitudinal axis of said tubular part when prolonged passing through said spherical part, one of said electrode leads being sealed into the tubular part of said container, the other of said leads being sealed into the spherical part of said container, said leads being immovably mounted in the same straight line coincident with the longitudinal axis of the tubular container part, said leads

terminating in the spherical part of said container, each of said leads having one of said electrodes mounted thereon, the discharge path between said electrodes being in the longitudinal axis of the tubular container part, the distance between said electrodes being less than the diameter of the spherical part of said container, a bell shaped open-ended baffle mounted in and affixed to the tubular part of said container and surrounding the current therein with the longitudinal axis thereof coincident with the longitudinal axis of the tubular container part, the larger end of said baffle being above the discharge path between said electrodes, the smaller end of said baffle being separated an appreciable distance from the closed end of the tubular container part, said baffle intercepting the sputtered particles of light absorbing material from said electrodes, and a heat reflecting metal coating on the outer surface of the tubular container part to maintain said tubular container part at as high a temperature as the spherical part of said container during the operation of said device.
